REFRIGERATING APPARATUS

Sylvester M. Schweller, Dayton, Ohio, assignor,
by mesne assignments, to General Motors Corporation, a corporation of Delaware

Application March 23, 1933, Serial No. 662,304
Renewed February 23, 1939

13 Claims.

(Cl. 62—3)

This invention relates to refrigeration and more particularly to a refrigerator compressor which operates continuously during the entire period of refrigeration requirement.

It is among the objects of this invention to provide a method of refrigerating a cabinet or the like and an apparatus for carrying out the method, in which the cabinet and the refrigerating system are so combined that the compressor can operate continuously during the entire period of refrigeration requirement of the cabinet and yet in which the temperatures desired in the cabinet may be easily and positively maintained without undue loss of power and without undue complications.

Further objects and advantages of the present invention will be apparent from the following description, reference being had to the accompanying drawings, wherein a preferred form of the present invention is clearly shown.

In the drawings:

Fig. 1 is a vertical cross-sectional view of an apparatus embodying features of this invention;

Fig. 2 is a view, partly in cross-section and partly diagrammatic of another apparatus;

Fig. 3 is a vertical cross-sectional view of a modification form of the invention shown in Fig. 1;

Fig. 4 is a vertical cross-sectional view of a portion of a form similar to that shown in Fig. 3, but slightly modified;

Fig. 5 is a vertical cross-sectional view of one of the evaporators shown in Figs. 2, 3 and 4; and

Fig. 6 is a vertical cross-sectional view of a detail.

Refrigerating apparatus and method embodying features of my invention are illustrated in Fig. 1, in which a cabinet, generally designated as 10 is refrigerated by a refrigerating system including a compressor 11, a condenser 12 and an evaporator 13 arranged in a closed cycle. The refrigerant flows from the compressor 11 to the condenser 12 and from thence, in liquid form, through the line 14 and through an interchanger 15 to an expansion valve 16. From thence the refrigerant flows through the evaporator 13 and returns to the compressor through the line 17. Under ordinary operation, the compressor 11 is driven continuously during the entire period of refrigeration demand by means of the electric motor 18, which may be a constant speed alternating current motor of the usual type. No switch, thermostatically responsive to temperatures within the cabinet or system need be provided for starting or stopping the compressor.

In the embodiment shown in Fig. 1, the cabinet 10 is provided with a food preserving space 19 within which the evaporator 13 is placed, and with a freezing space (not shown but similar to the space 32 hereafter described) within the hollow portion of the evaporator 13, preferably in the form of ice tray sleeves, now well known in the art. The system is controlled to maintain the desired temperatures in the food preserving space and the freezing space notwithstanding the continuous operation of the compressor. The temperature in the freezing space 20 generally is desired to be substantially below 32° F. and the temperature in the food preserving space 19 generally is desired to be above 32° F., and generally below 50° F.; but it is to be understood, that under varying conditions, the temperature requirements may be entirely different from those above specified. In order to maintain the desired temperatures, the evaporated refrigerant flowing from the evaporator 13 to the compressor 11 is throttled by a throttle valve 21, which throttle valve 21 is preferably of the thermostatic bulb variety, several of the details of which are shown in Fig. 6, and in which the thermostatic bulb 22 is made responsive not only to the temperature of the food preserving space 19, but also, because of its proximity to or contact with the ends of the ice tray sleeves, is also made responsive to the temperatures of the ice freezing space.

In the operation of the apparatus shown in Fig. 1, condensed liquid refrigerant flows through the line 14 to the heat interchanger 15 where it is cooled by the returning evaporated throttled refrigerant and from thence passes to the expansion valve 16. From thence the refrigerant flows through the evaporator 13 simultaneously cooling the food preserving space 19 and the freezing space 20 and returns past the throttling device 21 to the compressor 11. When the temperatures in the food preserving space and the ice freezing space have reached a sufficiently low temperature, the volatile fluid in the bulb 22 reduces the pressure in the bellows chamber 23 (see Fig. 6) of the throttling device and this causes the valve 21 to throttle the evaporated refrigerant returning from the evaporator 13 to the compressor 11. When temperatures in these spaces rises, such as by the introduction of water to be frozen in the space 20 or of warm food in space 19, the bulb 22 responds and opens the throttling valve partly or wholly to increase the refrigerating capacity of the evaporator. The relative areas of the evaporator 13 and the heat

exchange facilities between this evaporator and the two spaces is so arranged that under normal conditions the proper temperatures will be maintained in both spaces in response to actuations of the volatile fluid in the bulb 22.

In the modification shown in Fig. 3, the cabinet 30 is provided with a food preserving space 31 and a freezing space 32. A continuously operating compressor 33, driven by the constant speed motor 33a, supplies refrigerant to a condenser 34 from whence the refrigerant flows through the line 35 to the exchanger 36 and from thence, in parallel flow paths, through the evaporators or branches 37 and 38, the evaporated refrigerant returning through the lines or paths 39 and 40 respectively to the main suction line 41 and from thence back to the compressor 33 in a closed cycle. The evaporated refrigerant returning to the compressor from one of the evaporators, in this case the evaporator 37, is throttled by the throttling valve 42, similar to the valve 21, which valve 42 is made responsive in its throttling action to the temperature in the space 31 by means of the thermostatic bulb 43. The valve 42 and bulb 43 may also be substantially of the character shown in Fig. 6.

The operation of the apparatus shown in Fig. 3 is such that proper food preserving temperatures (above 32° F. and below 50° F.) are maintained in the space 31 by the throttling action of the valve 42, notwithstanding the continuous operation of the compressor 33, while the temperatures in the freezing space 32 are allowed to assume whatever temperature the refrigerating system is capable of maintaining therein; but the capacity of the refrigerating system is so made that it is sufficient to maintain temperatures in the space 32 below 32° F. If desired the freezing space 32 may be insulated from the food preserving space 31 by means of the insulated wall 45.

In the modification shown in Fig. 4, which is somewhat similar to that shown in Fig. 3, the compressor and condenser are substantially the same as shown in Fig. 3, the condensed liquid refrigerant flowing through the line 50 to the exchanger 51 and from thence, in parallel flow paths, to the evaporators or parallel branches 52 and 53. The evaporated refrigerant returns by means of the suction lines 54 and 55 respectively, through the interchanger 51 and back to the compressor (not shown, but similar to the compressor of Fig. 3) to close the cycle. In this modification, the return branch 55 from the evaporator 53 is also provided with a throttling valve 56, which is similar in its action to the throttling valves heretofore described, but, in this case, the throttling action is made responsive to the temperatures in the freezing space 57. In this modification, like in the modification shown in Fig. 3, the evaporated refrigerant leaving from the evaporator 52 is throttled by means of the valve 58 responsive to the temperatures in the food preserving compartment 59 through the medium of the thermostatic bulb 60.

In the modification shown in Fig. 2, the cabinet 70 includes a brine tank 71 in which one or more ice cream can sleeves 72 are placed so that ice cream cans may be introduced by the removal of the lids 73. The brine in the tank 71 is cooled by means of evaporator 74 which is part of the refrigerating system including the continuously operating compressor 75 and condenser 76. As is the case with the modification shown in Figs. 1, 3 and 4, the compressor 75 may be driven by the constant speed electric motor 77 which may be

actuated by direct or alternating current in the well known manner. In this case, the evaporated refrigerant returning from the evaporator 74 to the compressor 75 is throttled by means of a valve 78 responsive to the temperatures of the brine 79 through the medium of the thermostatic bulb 79. As is the case with all of the throttling valves heretofore described and shown in Figs. 1, 3 and 4, the valve 78 is made substantially as shown in Fig. 6.

The evaporators shown in Figs. 2, 3 and 4, may be of the well known flooded type having a float controlled inlet valve, the float maintaining a substantially constant level of refrigerant within the evaporator. To this end these evaporators 15 may be provided with a header 80, see Fig. 5, which contain the inlet valve 81 and the float control therefor 82. The liquid refrigerant is fed to downwardly directed heat exchangers 83, which may be circular or plate-like ducts into 20 which the liquid refrigerant flows and from which the evaporated refrigerant rises. The evaporated refrigerant leaves through the funnel 84 and returns to the compressor as heretofore described.

The throttling valves heretofore described may 25 be similar to that shown in Fig. 6. In this instance the line returning from the evaporator enters at 85 and leaves through the line 86 to the compressor. A throttling valve 24 is connected to the rod 86a which is sealed against the 30 escape of refrigerant by the bellows 87. The thermostatic bulb 88 creates pressures in the chamber 23 which, acting on the bellows 89 varies the throttling action of the valve 24 in accordance with the temperatures acting on the bulb 88. The 35 responsiveness of the valve to the cabinet temperatures affecting the bulb 88 may be varied, so that the system may be caused to maintain different temperatures in the compartment wherein the bulb 88 is placed. To this end the 40 spring 90 abuts against the adjustable screw 91 having a pointer handle 92. By returning the handle 92, with which a numbered temperature indicator dial, not shown, may be associated, the tension of the spring 90 may be varied, and this 45 varies the responsiveness of the valve to the temperatures affecting the bulb 88.

A manually operated switch may be provided for stopping the compressor for repairs, or, very infrequently, for defrosting. This switch need 50 not be operated to maintain cabinet temperatures during the period of refrigeration demand.

The throttling action of the valves heretofore described reduces the load on the compressor, so that, when the valves are nearly closed, the 55 compressor practically idles and consumes practically no power. By eliminating the stopping and starting problems usual with a thermostatic switch, efficiency is enhanced and cost of production is reduced.

While the form of embodiment of the invention as herein disclosed constitutes a preferred form, it is to be understood that other forms might be adopted, all coming within the scope of the claims which follow.

What is claimed is as follows:

1. The method of refrigeration of a cabinet or the like by means of a system having a compressor, condenser and evaporator in a closed cycle, which comprises operating the compressor continuously during the entire period of refrigeration requirement of said cabinet, throttling the return of evaporated refrigerant from said evaporator to said compressor in accordance with cabinet temperatures and cooling condensed re- 75

frigerant before entrance in said evaporator by means of evaporated refrigerant after it has been throttled.

2. A refrigerating apparatus comprising a cabinet or the like, a refrigerating system for refrigerating said cabinet including a compressor, condenser and evaporator in a closed cycle, said compressor operating continuously during the entire period of refrigeration requirement of said cabinet, means for throttling the return of evaporated refrigerant from said evaporator to said compressor in accordance with cabinet temperatures, and means for cooling condensed refrigerant before entrance into said evaporator by evaporated refrigerant after it has been throttled.

3. A refrigerating apparatus comprising a cabinet having a freezing space and a food preserving space, a refrigerating system for refrigerating said cabinet including a compressor, condenser and two evaporators in which the refrigerant flows in a closed cycle and in which said evaporators form parallel paths in said cycle between said condenser and compressor, said compressor operating continuously during the entire period of refrigeration demand of said cabinet, one of said evaporators cooling said freezing space and the other of said evaporators cooling said food preserving space, means for throttling the return of evaporated refrigerant from one of said evaporators to said compressor in accordance with temperatures in one of said spaces, and means for cooling condensed refrigerant before entrance into one of said evaporators by means of evaporated refrigerant after it has been throttled.

4. The method of refrigeration of a cabinet having a freezing space to be maintained below 32° F. and a food preserving space to be maintained above 32° F. by means of a system having a compressor, condenser and evaporators in a closed cycle and said freezing space being an insulated space within said food preserving space, which method comprises operating the compressor continuously during the entire period of refrigeration requirement of said cabinet, cooling said freezing space and said food preserving space by means of said evaporators by operating them at different intensities, and throttling the return of evaporated refrigerant from one of said evaporators to said compressor in accordance with temperatures in said freezing space and food preserving space.

5. The method of refrigeration of a cabinet having a freezing space to be maintained below 32° F. and a food preserving space to be maintained above 32° F. by means of a system having a compressor, condenser and two evaporators in which the refrigerant flows in a closed cycle and in which said evaporators form parallel paths in said cycle between said condenser and compressor and said freezing space being an insulated space within said food preserving space, which method comprises operating the compressor continuously during the entire period of refrigeration requirement of said cabinet, cooling said freezing space by means of one evaporator and cooling said food preserving space by the other of said evaporators.

6. The method of refrigeration of a cabinet having a freezing space to be maintained below 32° F. and a food preserving space to be maintained above 32° F. by means of a system having a single compressor, condenser and two evaporators in which the refrigerant flows in a closed cycle and in which said evaporators form parallel

paths in said cycle between said condenser and compressor and said freezing space being an insulated space within said food preserving space, which method comprises operating the compressor continuously during the entire period of refrigeration requirement of said cabinet, cooling said freezing space by means of one evaporator and cooling said food preserving space by the other of said evaporators, and throttling the return of evaporated refrigerant from one of said evaporators.

7. The method of refrigeration of a cabinet having a freezing space to be maintained below 32° F. and a food preserving space to be maintained above 32° F. by means of a system having a single compressor, condenser and two evaporators in which the refrigerant flows in a closed cycle and in which said evaporators form parallel paths in said cycle between said condenser and compressor and said freezing space being an insulated space within said food preserving space, which method comprises operating the compressor continuously during the entire period of refrigeration requirement of said cabinet, cooling said freezing space by means of one evaporator and cooling said food preserving space by the other of said evaporators, and throttling the return of evaporated refrigerant from each of said evaporators.

8. The method of refrigeration of a cabinet having a freezing space to be maintained below 32° F. and a food preserving space to be maintained above 32° F. by means of a system having a compressor, condenser and evaporator in a closed cycle and said freezing space being an insulated space within said food preserving space, which method comprises operating the compressor continuously during the entire period of refrigeration requirement of said cabinet, cooling said freezing space to a temperature below 32° F. and said food preserving space to a temperature above 32° F. by means of said evaporator, and throttling the return of evaporated refrigerant from said evaporator to said compressor in accordance with temperatures in said freezing space and food preserving space.

9. The method of cooling a plurality of compartments by means of a system having a compressor, condenser and a plurality of evaporators in a closed cycle, which method comprises operating the compressor continuously during the entire period of refrigeration requirement of said compartments, cooling said compartments to different temperatures by means of said evaporators, and throttling the return of evaporated refrigerant from said evaporators to said compressor in accordance with temperatures in said compartments.

10. The method of refrigerating separate spaces by means of a refrigerating system having a compressor-condenser unit and a plurality of evaporators connected in closed circuit relation which comprises, operating the compressor-condenser unit continuously during the entire period of refrigeration requirement of the spaces, cooling one space by means of one of said plurality of evaporators and cooling the other space by means of another of said plurality of evaporators, and throttling the return of evaporated refrigerant from said one evaporator to said compressor-condenser unit in accordance with the temperature of one of said spaces while permitting unrestricted return of evaporated refrigerant from said another evaporator to said compressor-condenser unit to operate the evap-

orators at different intensities relative to one another.

11. The method of refrigerating separate spaces by means of a refrigerating system having a compressor-condenser unit and a plurality of evaporators connected in closed circuit relation which comprises, operating the compressor-condenser unit continuously during the entire period of refrigeration requirement of the spaces, 5 cooling one space by means of one of said plurality of evaporators and cooling the other space by means of another of said plurality of evaporators, throttling the return of evaporated refrigerant from said one evaporator to said compressor-condenser unit in accordance with the temperature of one of said spaces while permitting unrestricted return of evaporated refrigerant from said another evaporator to said compressor-condenser unit to operate the evaporators at different intensities relative to one another, and transferring heat from refrigerant supplied to said evaporators to the refrigerant returning to said compressor-condenser unit. 10
12. The method of refrigerating separate spaces by means of a refrigerating system having a compressor-condenser unit and a plurality of evaporators connected in closed circuit relation which comprises, operating the compressor-condenser unit continuously during the entire period of refrigeration requirement of the spaces, 15 cooling one space by means of one of said plurality of evaporators and cooling the other space by means of another of said plurality of evaporators, throttling the return of evaporated refrigerant from said one evaporator to said compressor-condenser unit in accordance with the temperature of the space cooled thereby, throttling the return of evaporated refrigerant from 20 said another evaporator to said compressor-condenser unit in accordance with the temperature of the space cooled thereby to operate the evaporators at different intensities relative to one another, and transferring heat from refrigerant supplied to said evaporators to the refrigerant returning to said compressor-condenser unit. 25

13. The method of refrigerating separate spaces by means of a refrigerating system having a compressor-condenser unit and a plurality of evaporators connected in closed circuit relation which comprises, operating the compressor-condenser unit continuously during the entire period of refrigeration requirement of the spaces, cooling one space by means of one of said plurality of evaporators and cooling the other space by means of another of said plurality of evaporators, throttling the return of evaporated refrigerant from said another evaporator to said compressor-condenser unit in accordance with the temperature of the space cooled thereby to operate the evaporators at different intensities relative to one another. 30
